UNITED STATES PATENT OFFICE.

ALFRED ISHERWOOD, OF NEW BEDFORD, MASSACHUSETTS.

LOOM-SHUTTLE.

1,070,963.

Specification of Letters Patent. Patented Aug. 19, 1913.

Application filed July 27, 1909. Serial No. 509,861.

To all whom it may concern:

Be it known that I, ALFRED ISHERWOOD, a citizen of the United States, and a resident of New Bedford, in the county of Bristol and State of Massachusetts, have invented a new and useful Improvement in Loom-Shuttles, of which the following is a specification.

My invention relates to loom shuttles and 10 more particularly to threading devices for self-threading shuttles such as are used in automatic filling-replenishing looms or for common shuttles.

In a common shuttle the free end of the 15 thread or filling from the bobbin is usually sucked or drawn through the shuttle-eye by the mouth of the operator. In a self-threading shuttle, in which the side of the shuttle at the threading end is slotted or cut down, 20 or otherwise constructed to allow the free passage of the thread, the threading may be done manually or substantially automatically. It frequently happens, however, that during the operation of threading an automatic shuttle, the thread fails to pass 25 through the eye and it also happens with both kinds of shuttles that occasionally the thread is ballooned outwardly or overthrown by the sudden stopping of the shuttle at the end of its throw thereby necessitating 30 the stopping of the loom.

It is therefore one of the objects of my invention to provide a device whereby an automatic or common shuttle may be threaded 35 either automatically or by hand, or partially automatically and partially by hand in a more positive manner than is possible with the shuttles now in use, and whereby such ballooning or outward overthrowing of 40 the thread may be prevented; and other objects are to provide a new and simple tension device which may be used separately or 45 in conjunction with my threading device, and generally to improve the construction of 50 shuttles in the manner hereinafter set forth.

Several embodiments of my invention are shown in the drawings which accompany and form a part of this specification; but it will be understood that various modifications 55 may be made by those skilled in the art without departing from the principle of my invention.

In the drawings Figure 1 is a plan view 5 of the thread or delivery end of one form of my improved shuttle. Fig. 2 is a longitudinal section taken on the line 2-2 of Fig.

1. Fig. 3 is a transverse section taken on the line 3-3 of Fig. 1 looking in the direction of the arrow. Fig. 4 is a plan view of the delivery end of a shuttle of the general type 60 of that shown in Fig. 1 with the threading device removed, and shows a modification of the shuttle shown in Fig. 1. Fig. 5 is a side view of the threading block removed from the shuttle and represents a modification 65 adapted for use with the shuttle shown in Fig. 4. Fig. 6 is an end view of the threading device shown in Fig. 5. Fig. 7 is a plan view of the delivery end of a common shuttle constructed in accordance with my invention. Fig. 8 is a side view of the shuttle shown in Fig. 7. Fig. 9 represents the blank from which the eye of my improved 70 shuttle may be formed. Fig. 10 is a plan view of the eye made from the blank shown 75 in Fig. 9, and adapted for use with the shuttles shown in Figs. 1, 4 and 8. Fig. 11 is a transverse section of the eye shown in Fig. 10 looking in the direction of the arrow. Fig. 12 is a side view of a common shuttle 80 such as shown in Fig. 8 provided with a modified form of eye. Fig. 13 represents a blank from which said modified form of eye may be made. Fig. 14 is a plan view of the eye made from the blank shown in Fig. 85 13. Fig. 15 is a transverse section of the eye shown in Fig. 14 taken on the line 15, 15 looking in the direction of the arrow. Fig. 16 is a transverse section of a portion of the shuttle shown in Fig. 12 taken on a line 90 parallel to the length of the shuttle near the delivery end of the eye 7'. Fig. 17 is a plan view of one form of guard that may be used with the shuttle shown in Fig. 7. Fig. 18 is an edge view of said guard. Fig. 95 19 is a front view of the guard shown in Fig. 17. Fig. 20 is a plan view of a common shuttle such as shown in Fig. 7 provided with a modified form of guard. Fig. 21 is a transverse section taken on the line 21, 21 100 of Fig. 20. Fig. 22 is a perspective view of the guard shown in Fig. 20. Fig. 23 is an end view of another form of guard that may be employed in connection with the shuttle shown in Fig. 20. Fig. 24 is a central section, and Fig. 25 is a plan view, of 105 the guard shown in Fig. 22.

In the drawings selected for illustrating the principle of my invention, 1 represents a self-threading shuttle provided with the 110 usual metallic tip 2 and having a threading-block 3 removably inserted in the throat or

delivery-end and held in position by a bolt 3' or by other suitable means. The threading-block which may be cast in brass or other suitable metal resembles in its general structure that shown and described in the patent to Northrop No. 926,016, dated June 22, 1909 and does not constitute a part of my invention except as hereinafter specified. The threading-block is provided with a slot 5 for receiving the thread A from the bobbin and has a guard 4 overhanging said slot and provided with a lateral extension 4'' extending outwardly toward the delivery-end of the shuttle. The downwardly and the 10 rearwardly extending portion 4 of the guard is placed opposite a groove 4' in the threading-block. The threading-block is also provided with a rearwardly and inwardly extending beak 6 which projects into the circumferential portion 8 of a slot in the eye 7 and serves as hereinafter set forth to guide the thread into said eye.

The eye 7 is preferably formed from a blank shown in Fig. 9 and is approximately 15 circular in section throughout a portion of its length. This eye is provided with the above mentioned slot 8 which intersects the longitudinal slot 8' and the latter terminates in a circular hole 14 on the upper side of the 20 eye. The inner lip 13 is formed by bending the portion of the blank shown at 13 in Fig. 9 under the surface of the eye so that the lip underlies a portion of the longitudinal slot 8' as most clearly shown in Fig. 10. The delivery-end of the eye near the front wall of the shuttle is provided with two downwardly extending curved lips 15 and 16 formed by bending the portions of the blank designated as 15 and 16 in Fig. 9.

25 The essential features of my invention as so far described consist in the guard 4, 4'' with its co-operating slot 4', the guiding beak 6 and the eye with its inner and outer lips.

When the shuttle above described is threaded either automatically or manually, the free 30 end of the thread A from the bobbin is passed over the guard 4, the slot 4' permitting this to be easily done, through the slot 5 and under the hook 17, as the shuttle moves inwardly, and then as the shuttle moves outwardly the thread passes over the beak 6 and is guided thereby into the slot 8 of the eye, and then further outward movement of the shuttle causes the thread to pass over 35 the inner lip 13 into the slot 8' and thence into the hole 14. The thread then passes through the space between the shuttle and the lip 15 which extends slightly below the transverse hole bored in the shuttle for receiving the eye 7 (as shown in Fig. 8) and is thereby prevented from leaving the eye. At the completion of the threading operation, the position of the thread in the shuttle is as 40 shown at A A in Fig. 1.

45 65 In the modifications shown in Figs. 4, 5

and 6 the function of the outer lip 15 substantially is performed by the pin 10 which projects from the threading-block and passes into the slot 9 near the front wall of the shuttle. Furthermore by constructing this pin to fit fairly tightly in the slot, the thread may be placed under tension, the amount of which depends upon the closeness of the fit of the pin in the slot, and in such case the usual flannel tension shown at B may be eliminated. The eye 7 which I have described above in connection with the automatic shuttle may also be employed in the common shuttle shown at 1' in Figs. 7 and 8, in which the delivery end of the shuttle is provided with the slot 11 extending as shown diagonally across the top of the shuttle and having its inner end terminating at the slot 8 of the eye and intersecting the longitudinal slot 12 formed in the front side of the shuttle. In this case the operator instead of sucking the thread through the eye, grasps one end of the thread and passes it through the slot 11 thereby bringing it into the slot 8 of the eye and then draws it inwardly through the slot 12, thereby causing the thread to enter the slot 8', to pass under the lip 13 and out into the hole 14, and finally to pass between the shuttle and the lip 15, whereupon the shuttle is threaded and the position of the thread in the shuttle is as shown in Fig. 7 at A A.

In order to prevent the outward ballooning of the thread I may employ a guard which may also perform the function of a tension device. This guard which is shown in detail in Figs. 17, 18 and 19, consists of a base 20 which is held in adjustable position in two slots cut in the throat of the shuttle, an upwardly extending piece 20' substantially at right angles to said base and an outwardly extending flat piece 17, the corner 18 of which enters a groove in the shuttle above the eye 7 and is firmly held in position thereby. The piece 17 is provided with a rearwardly extending lip or offset 19, which as shown in Fig. 7, fits loosely into a slot in the shuttle, the slot being large enough to permit the thread to pass over said lip. The flat piece 17 is curved throughout its length on its rearward side as shown in Figs. 7 and 17. 22 is an eye which I may call a tension-eye consisting of a slit in the inward end of the guard, and 21 is an upwardly extending guard for said eye. The eye 22 is so positioned with respect to the hole 14 in the top of the eye 7 as to put the thread under tension, and in the present instance the eye 22 is placed below the hole 14 so that the thread must pass up an incline from the eye 22 to the top of the eye 7. The tension on the thread may be regulated by turning the eye 7 in its socket. When the guard just described is employed, the thread is brought through the slot 11 and then the 1

inward movement of the thread through the slot 12 will draw the thread over the lip 19 and in the slot into which said lip projects, and then over the guard 21 and into the eye 22, and finally into the eye 7 in the manner hereinbefore described.

It will be understood from the above description that the eye 7 may be employed with an automatic or a common shuttle, either with the usual flannel tension or with the metallic tension described in connection with Figs. 4, 5 and 6, and that if used in a common shuttle it may be employed with or without the combined guard and tension device described in connection with Figs. 17, 18 and 19, or with any other tension device.

In Fig. 14 I have shown a modified form of eye that may be employed in either the automatic or common shuttle. This eye 7' is provided with the circumferential and longitudinal slots 8, 8', the lip 13 and hole 14, all as above described in connection with Fig. 9. The hole 23 is cut in the wall of the eye near the delivery-end thereof and the interior tongue 23' is bent to coöperate with said hole. In order to prevent undue tension on the thread as it passes between the tongue and hole, a portion of the shuttle may be cut away to form the recess shown at 24. In threading a common shuttle provided with the eye 7' the thread on passing through the slot 12 enters the slots 8 and 8' of the eye as hereinbefore described and then passes from the bottom of the eye-socket to the eye between the tongue 23' and hole 23, the said tongue which may project slightly into said hole serving to prevent the thread from leaving the delivery-end of the eye.

It will be understood that any suitable tension device, such as that shown in Fig. 18, may be employed in connection with the eye 7' as shown in Fig. 12. In Fig. 20 I have shown another type of guard to prevent outward ballooning. This guard consists essentially of the base 25 which slides through grooves in the throat of the shuttle to insure the proper positioning of the guard and two upwardly extending members, one of which shown at 27, is an inverted U-shaped member provided with a hole 28, and the other a tongue 26 projecting into and coöperating with said hole. During the process of threading the shuttle, the thread will pass between the tongue and member 27 and will be thereafter prevented from leaving the guard and overthrowing into the slot 11 or catching on any other portion of the shuttle or loom. It will be understood that, the guards shown in Figs. 20 and 23 may be employed with any suitable tension device and that as required in certain classes of weaving the tension device may be omitted.

In Figs. 23, 24 and 25 I have illustrated another type of guard located between the

eye and the bobbin for the purpose of preventing the overthrowing of the thread. This guard comprises a base 32 which slides through grooves in the throat of the shuttle in the manner illustrated in Fig. 20 with respect to the base 25 of the guard therein shown. The base 32 carries two right-angled over-lapping members 29 and 30, the member 29 corresponding to the tongue 26 of the guard shown in Fig. 20 and the member 30 corresponding to the piece 27 shown in said figure. The members 29 and 30 overlap and the latter may be provided with a hole 31 into which the tongue-shaped member 29 projects and with which it co-operates to prevent the thread leaving the guard. The members 29 and 30 may as shown extend beyond their upright supports and the lateral extensions 33 may, if desired, slide in grooves cut in the throat of the shuttle to prevent the thread from catching in the space which otherwise might be left between the guard and inner wall of the shuttle.

In order to more clearly define the several elements of my invention I adopt the same definitions of the terms "frontward" and "rearward" as applied to the walls of the shuttle and the terms "inward" and "outward" as applied to the direction of the shuttle in operation as have been set forth in the patent to Northrop aforesaid.

I claim:

1. A loom-shuttle having a removable delivery eye inserted transversely in the throat of the shuttle and provided with a slot, and a lip in the interior of said eye adjacent to said slot, said lip passing under and extending across and beyond said slot.

2. A loom-shuttle having a removable delivery-eye inserted transversely in the throat of the shuttle and provided with a slot, one portion of said slot being circumferential and the other portion thereof at right angles to the first portion being longitudinal of the eye, and a lip in the interior of said eye adjacent to and passing under the longitudinal portion of said slot, said lip being adapted to prevent the filling-thread from leaving said eye.

3. A loom-shuttle having a removable delivery-eye inserted transversely in the throat of the shuttle and provided with a slot, a lip in the interior of said eye adjacent to and passing under said slot, said lip being adapted to prevent the filling-thread from leaving said eye, and a tongue near the delivery-end of said eye, located adjacent to and coöperating with a hole in the wall of said eye.

4. A loom-shuttle having a removable delivery-eye inserted transversely in the throat of the shuttle and provided with a slot, one portion of said slot being circumferential and the other portion thereof at

- right angles to the first portion, being longitudinal of the eye, a lip in the interior of said eye adjacent to and passing under said slot and an interior tongue secured to the 5 eye near the delivery end thereof, said tongue being adapted to prevent the filling-thread from leaving the eye.
5. A loom-shuttle having a removable delivery-eye inserted transversely in the throat of the shuttle and provided with a slot, one portion of said slot being circumferential and the other portion at right angles to the first portion being longitudinal of the eye, a lip in the interior of said eye, adjacent to 10 and passing under the longitudinal portion of said slot, and a tongue secured to said eye near the delivery end thereof, said tongue being adapted to prevent the filling-thread from leaving the eye.
10. 6. A loom-shuttle having a removable delivery-eye inserted transversely in the throat of the shuttle and provided with a slot, one portion of said slot being circumferential and the other portion thereof at right angles to the first portion being longitudinal of the eye, a lip in the interior of said eye adjacent to and passing under the longitudinal portion of said slot, and a tongue near 15 the delivery end of said eye located adjacent to and coöperating with a hole in the wall of said eye.
7. A loom shuttle having a removable delivery eye inserted transversely in the throat of the shuttle and provided with a slot, and 20 a lip in the interior of said eye and adjacent to said slot, said lip being integral with said eye and consisting of a member bent back under the wall of the eye, the inner end of said member terminating beyond said slot.
20. 8. A loom shuttle having a removable delivery eye inserted transversely in the throat of the shuttle and provided with a slot, one portion of said slot being circumferential and the other portion at right angles to the 25 first portion, being longitudinal to the eye, and a tongue secured to said eye near the delivery end thereof, said tongue being adapted to prevent the filling-thread from leaving the eye.
25. 9. A loom shuttle having a removable delivery eye inserted transversely in the throat of the shuttle and provided with a slot, one portion of said slot being circumferential and the other portion thereof at right angles 30 to the first portion, being longitudinal of the eye, said shuttle being provided at its delivery end with a slot having its inner end terminating at the circumferential portion of the slot in said delivery eye, and a removable guard located between the eye and bobbin.
30. 10. A loom shuttle having a removable delivery eye inserted transversely in the throat of the shuttle and provided with a slot, one portion of the slot being circumferential and the other portion thereof at right angles to the first portion, being longitudinal of the eye, and a removable guard located in the throat of the shuttle between the eye and bobbin, said guard having a portion projecting into a recess in said throat.
35. 11. A loom shuttle having a removable delivery eye inserted transversely in the throat of the shuttle and provided with a three-part slot, one part being circumferential, another part being longitudinal and extending part way across the top of said eye toward the delivery end thereof, and the third part being longitudinal and extending from the lower end of said circumferential part to the delivery end of said eye.
40. 12. A loom shuttle having a removable delivery eye inserted transversely in the throat of the shuttle and provided with a three-part slot, one part being circumferential, another part being longitudinal and extending part way across the top of said eye toward the delivery end thereof, and the third part being longitudinal and extending from the lower end of said circumferential part to the delivery end of said eye, and a tongue secured to said eye near the delivery end thereof, said tongue being adapted to prevent the thread from leaving the eye.
45. 13. A loom-shuttle having a removable delivery eye inserted transversely in the throat of the shuttle, and a removable guard located in the throat of the shuttle between the eye and bobbin, said guard comprising a horizontal outwardly-extending flat piece having its rearward side curved throughout its length.
50. 14. A loom-shuttle having a removable delivery-eye inserted transversely in the throat of the shuttle and provided with a slot, one portion of said slot being circumferential and the other portion thereof at right angles to the first portion, being longitudinal to the eye, and a tongue near the delivery-end of said eye located adjacent to and coöperating with a hole in the wall of said eye.
55. 15. A loom-shuttle having a removable delivery-eye inserted transversely in, and extending across and beyond, the throat of the shuttle and provided with a slot, said shuttle being provided at its delivery end with a slot having its inner end terminating directly at the slot in said delivery-eye, and the slot in said shuttle being inclined toward the rearward wall of the shuttle, so that the slotted portion of the shuttle overhangs the slotted portion of said delivery-eye.
60. 16. A loom-shuttle having a removable delivery-eye inserted transversely in the shuttle and provided with a slot, said shuttle being provided at its delivery-end with a slot having its inner part communicating directly with the slot in said delivery-eye at

- one side of the center of the throat of the shuttle and out of line with the longitudinal axis of the bobbin, so that the slotted portion of the shuttle overhangs the slotted portion of said delivery-eye. 5
17. A loom-shuttle having a removable delivery-eye inserted transversely in the shuttle, said shuttle being provided at its delivery end with a slot at one side of the center of the throat of the shuttle and out of line with the longitudinal axis of the bobbin, whereby during the threading operation the filling thread will be drawn transversely under cover to a point in line with said axis. 10
18. A loom-shuttle having a removable delivery-eye inserted transversely in the shuttle and provided with a slot, the end of said slot forming a stop arranged in line with the longitudinal axis of the bobbin, said shuttle being provided with a slot having its inner part communicating directly with the slot in the delivery-eye at one side of the center of the throat of the shuttle and out of line with the longitudinal axis of the 15
- bobbin, whereby during the threading operation the filling thread will be drawn under cover along the slot to the stop. 25
19. In a loom-shuttle having a removable delivery-eye inserted transversely in the shuttle and provided with a slot, said shuttle being provided with a slot communicating with the slot in the delivery-eye at one side of the center of the throat of the shuttle and out of line with the longitudinal axis of the bobbin, the slot in said eye extending longitudinally thereof and its end forming a stop arranged to hold the filling thread in line with the longitudinal axis of the bobbin, whereby the filling thread will be drawn along the slot under cover to the stop during the threading operation. 30 35
- In testimony whereof, I have hereunto subscribed my name this 13th day of July 1909.

ALFRED ISHERWOOD.
